CARTRIDGE FOR DISPENSING LIQUID CHEMICALS

Philip Alexander, New York, N. Y., assignor, by
mesne assignments, to Charles C. Trelease,
Newark, N. J., as trustee

Application March 22, 1946, Serial No. 656,234

2 Claims. (CL 222—82)

1

This invention relates to the dispensing of liquid chemicals, liquid gases, suspensions of finely divided solids, or other fluids from an enclosed vessel by means of compressed gases or other suitable propellents, and more particularly to a suitable method and means for sealing such chemicals or fluids within the container and for permitting quick and easy discharge of any part or all of the contents.

An object of this invention is to provide a plastic sealing element of rubber, synthetic rubber, soft plastic or a similar material so constructed as to permit filling passages through which the fluids and the propellents may pass during the filling operation and after the mechanical closure, form an effective leak-tight seal.

A further object of the invention is the provision of a sealing element, as described above, so constructed as to permit piercing thereof by a hollow tubular metal pin, for the purpose of discharging the contents of the container.

Another object is the provision of a sealing element, as described above, so constructed that when the discharge tube is withdrawn, the internal pressure on the element will cause it to reseal itself, so that the container may be reused on several occasions until the contents are exhausted.

Still another object is the provision of a dispensing device that is simple in construction and small in size for easy handling, whereby a large variety of liquid products may be sprayed, atomized or discharged in desired quantities with a minimum of effort and waste.

With these and other objects in view, as may appear from the following specification, the invention consists of the following described method of sealing and dispensing liquids and of various features of construction and combinations of parts, as described in connection with the accompanying drawings, the features forming the invention being specifically pointed out in the appended claims.

In the drawings:

Figure 1 is a longitudinal section through a container capsule and a sealing device therefor;

Figure 2 is a view similar to Figure 1, showing the sealing device assembled with the container;

Figure 3 and Figure 3-A are perspective views of one form of the sealing element, in upright and inverted positions, respectively;

Figure 4 and Figure 4-A are perspective views of a modified form of the sealing element, in upright and inverted positions, respectively;

Figure 5 is a view, partly in central section and

2

partly in elevation, of a container and sealing element, as illustrated in Figure 3, prior to completion of the assembly;

Figure 6 is a view, partly in section and partly in elevation, of a container and sealing element, as illustrated in Figure 4, prior to completion of the assembly;

Figure 7 is a view in central section showing still another sealing construction;

Figure 7-A is a perspective detail of a washer of Figure 7;

Figure 8 is a sectional view showing the method of filling and sealing;

Figure 9 is a view showing the container of Figures 5 and 6, as completed;

Figure 10 is a sectional view of the completed container constructed according to Figure 7;

Figure 11 is a sectional view of the container and sealing device embodying the present invention, with a dispensing device inserted therein;

Figure 12 is a sectional view similar to Figure 11, showing the dispensing device partially removed therefrom; and

Figure 13 is a sectional view similar to Figures 11 and 12, showing the container and sealing device following removal of the dispensing device therefrom.

Referring more particularly to the drawings, in Figure 1 is illustrated a metal container capsule *b* of a general type and design commonly available on the market, having a circular or round neck *1* formed thereon to provide a mouth or opening *2* for the container. The opening *2* has a recess *3* formed therein, leaving a shoulder *4* a short distance inward from the mouth of the opening *2*.

A small sealing plug *a* is shown, of a diameter somewhat less than the diameter of the recess *3*, and which fits therein and rests upon the shoulder *4*.

A primary form of the plug *a* is illustrated, in cross-section, in Figure 1. The plug comprises a main cylindrical body *5* of a thickness slightly less than the depth of the recess *3*, or than the distance from the shoulder *4* to the mouth of the opening *2*. This cylindrical body *5* has a cone-shaped concave recess *6* formed in its upper surface, of a diameter preferably less than the diameter of the body *5*. On its lower surface is formed a hemispherical dome or protuberance *7*, also of a diameter less than that of the body *5*, leaving a shoulder *8* on the lower surface of the body *5* for cooperation with the shoulder *4* formed by the recess *3*.

The plug *a* is made of a soft, elastic plastic

material, such as rubber, synthetic rubber, soft plastic or a similar material. The particular material to be used depends largely upon the qualities of the material to be dispensed. If the contents of the container are of an oily nature, a material such as "neoprene," impervious to oils, will be desirable. A typical material to be dispensed is the insecticide known as D. D. T. and used in the form of an oil suspension. Many other fluids may, however, be handled. The plug must have sufficient hardness to resist extrusion under high pressure, and must be of such density as to permit easy piercing by a hollow tubular pin, and to be self-sealing when such pin is withdrawn. It should be of such elasticity as to not clog the piercing pin when it is inserted therein.

When the container *b* has been filled with a fluid *c*, under pressure, as illustrated in Figure 2, the mouth portion of the container wall is folded or crimped over the sealing plug *a* so as to firmly seal it in a secure and leak-proof position. The method of filling and sealing the container will be discussed more fully hereinafter.

Figures 3 and 4 illustrate, in greater detail, two possible forms of the plug *a* depicted in Figure 1, either of which may be satisfactorily used. Figure 3 comprises two perspective views of one of these forms, *a*-1, the upper and lower views showing it in upright position and in inverted position, respectively. In this form, the shape of the plug is substantially the same as shown and described in connection with Figure 1, but showing more clearly a plurality of radial projections *9*, formed on the lower surface or shoulder *8* of the body *5*. These projections may be of any desired shape, being shown as substantially wedge-shaped. They extend from the walls of the dome *7* to the periphery of the body portion *5*.

Figure 4 comprises similar perspective views of a modified form of the plug, indicated as *a*-2. It is substantially identical to that shown in Figure 3, differing in that a plurality of small indentations or channels *10*, radiating from the periphery of the dome *7*, are formed in the lower surface or shoulder portion *8* of the body *5*.

In Figure 5 is illustrated the cooperating relation of the sealing plug to the container, before or during the filling of the latter with gas or fluid. The form of plug *a*-1 is shown as placed within the recess *3* formed in the neck *1* of the container *b*. The projections *9* formed on the shoulder *8* of the body *5* rest upon the shoulder *4* formed in the opening *2*. The dome portion *7* is adjacent the interior of the container *b* and the concavity *6* faces outward.

Figure 6 is similar to Figure 5, substituting the form of plug *a*-2 illustrated in Figure 4. Here the shoulder *8* and indentations *10* formed therein are adjacent the shoulder *4*.

Referring to both Figures 5 and 6, the diameter of the recess *3* of the opening *2* is larger than the diameter of the body *5* of the plug placed therein, leaving a space thereabout which cooperates with the openings formed between the projections *9* in the one form, or the openings formed by the channels *10* in the second form, to provide a flow passage for the liquid being introduced into the container *b*.

The method of filling and sealing the container *b* is illustrated in Figure 7. A neck or spout *e* of a suitable filling and sealing machine, the general structure of which is not shown or described since it forms no part of this invention, is shown. Any type of such machine usually used for the purpose may be adapted for use with the present

invention. A recess *20* is formed in the end of the spout *e* to receive the neck *1* of the container *b*. The recess *20* is formed to closely fit the exterior of the neck *1*, and an opening *21* connects with the interior of the recess *20* for passage of the liquid or gas with which the container is to be filled. When the container is to be filled, the neck or spout *e* is placed over the neck *1* of the container in the position shown in dotted lines. The liquid or gas flows from the passage *21* into the recess *20*, between the sides of the sealing plug and the walls of the recess *3* formed in the container *b*, through the openings formed between the projections *9*, or by the channels *10* as the case may be, and into the container *b*. When the container *b* is full, the neck or spout *e* of the filling mechanism is forced downwardly, under pressure, so that the bottom of the recess *20* will fold inwardly the upward extending walls of the neck *1* against the upper surface of the plug to crush the body of the plug downward and outward and form a seal. A portion of a container *b* and the sealing plug, after the seal has been formed, is shown in cross-section in Figure 9. Gas for providing pressure may be placed in the container along with the material to be dispensed, or solid carbon dioxide or other gas producing material may be utilized for developing pressure after sealing.

30 In forming the walls of the neck *1* to compress the sealing plug, the filling projections *9* of the plug *a*-1 are so compressed as to form a complete seal on all areas where the plug contacts the wall *3* or the shoulder *4* of the container *b*. 35 Due to the compression of the projections *9*, the shoulder *8* will rest solidly against the shoulder *4*. If the form of plug *a*-2 is used, the compression will close up the channels or indentations *10* to produce the same sealing effect. In addition, the 40 compression of the body of the plug will cause it to spread to some degree, resulting in a sealing relation between the walls of the body portion *5* and the walls of the recess *3*.

A modification of the above, employing a protective metal washer *d* is illustrated in Figures 7, 45 7-A and 10. This metal washer *d* may be used in conjunction with either of the above described forms of sealing plug. The washer *d* comprises a flat ring having a concave portion *30* formed at its center, adapted to conform to the concave recess *6* formed in the plug. A central opening *31* is formed in the washer *d* for receiving a piercing needle or tube, when the contents of the container are to be dispensed. This metal support washer *d* may be provided, when desired, to prevent the sealing plug used therewith from being extruded when the contents of the container are under extraordinarily high pressures, and also as a guide for the piercing needle or tube.

50 In Figure 11 is shown a piercing and dispensing unit *40* for use with the above described container and sealing plug. It comprises a housing *41* in which is mounted a tube *42* of such internal diameter as to secure the desired particle size, 55 atomization, spray or dispensing quality, when used in combination with the particular liquid or chemical under a predetermined pressure within the container *b*. The housing *41* of this unit *40* has a recess *43* formed therein to fit neatly over the mouth or neck *1* of the container *b*. The tube *42* is tapered or chamfered at its inner end to form a sharp edge for the purpose of piercing the plastic seal. The tube *42* is shown as extending upwardly within the housing *41* and then at right angles to an opening in the side of the housing.

It is to be understood, however, that the tube may open through the top of the housing 41, where so desired.

When it is desired to use the spraying device, the point of the tube 42 is placed at the center or lowest point of the concavity 6 and a downward pressure exerted against the tube 42 through its associated housing 41 to pierce the plug and insert the end of the tube into the container b. The recess 43 fits snugly over the neck 1 of the container b, although allowing the housing 41 to be rotated with relation to the container, if desired, to change direction of discharge. When the tubular piercing pin 42 has completely passed through the sealing plug a, the opening in the pin is exposed to the fluid contents c of the container b, and since the contents are under pressure, the liquid is forced through the tubular pin and released through the orifice 44 into the air. By revolving either the container or the housing 41, the direction of the spray or discharge may be controlled.

After the desired amount of the contents has been discharged, the piercing and dispensing unit 40 may be withdrawn and the opening within the plug made by the piercing tube will automatically seal itself, as illustrated in Figures 12 and 13. The pressure within the container, directed against the domed structure of the sealing ring in an outward direction, forces the walls of the puncture together and efficiently and completely seals the container, so that the remaining contents may be used at a later time. When it is desired to use the remainder of the contents, the dispensing unit 40 is again inserted through the sealing plug. As is clearly disclosed in Figure 12 of the drawings, the resealing action is instantaneous, the lower part of the puncture being closed as quickly as the end of the tube is withdrawn. Thus there is no possibility of loss of pressure or leakage of the contents of the container as the tube is withdrawn. A positive, instantaneous resealing is assured.

With the present device for sealing and dispensing, the entire contents of a container need not be used at one time, but may be dispensed at intervals over an indefinite period, without waste. In the usual device provided for this purpose, once the container seal has been broken, the entire contents must be used immediately since no provision has heretofore been provided for resealing such a container for future use. The present resealing device provides as efficient a seal after the second, third or fourth use as originally existed before any of the contents of the associated container were dispensed, a distinct advantage and improvement over similar devices, since many products marketed in this form are highly concentrated and often expensive, and only very small quantities are desired to be used at one time.

What is claimed is:

1. In a sealing and dispensing device for fluids under pressure including a container therefor having a discharge opening, the combination of a solid closure body for said opening formed of

rubber or similar soft resilient plastic material, said closure body being inwardly domed in form, solid within its domed portion and having an annular flange thereon of less diameter than said opening, an annular washer having a flat rim of substantially the same diameter as said flange and a conical central portion for supporting said closure body against pressure from within said container and for guiding a dispensing tube centrally thereof for piercing said closure body, and means for holding said flange and said washer in compressed relation with the walls of said opening for sealing the same.

2. In a sealing and dispensing device for fluids under pressure including a container therefor having a cylindrical neck, the combination of a recess formed in said neck to provide a shoulder therein, a cylindrically shaped closure body for said opening of less diameter than said recess and adapted to rest upon said shoulder, said closure body being formed of rubber or similar soft resilient plastic material adapted to be pierced by a hollow dispensing tube, said closure body also having a concave outer surface and convex inner surface and passages formed in its lower surface to allow passage of fluid between said body and said shoulder, an annular washer having a flat rim and a conical central portion conforming to the concave outer surface of said body for supporting the same against excessive pressure from within said container and for guiding said dispensing tube centrally of said body, and means for holding said washer and said closure body in compressed relation with said shoulder to close said passages and seal said opening.

PHILIP ALEXANDER.
